DESIGN FOR A DESK

Max Livon, Minneapolis, Minn.

Application April 23, 1945, Serial No. 119,151

Term of patent 14 years

(Cl. D71—1)

To all whom it may concern:

Be it known, that I, Max Livon, a citizen of the Dominion of Canada, residing at Minneapolis, in the county of Hennepin, and State of Minnesota, have invented a new, original, and ornamental Design for a Desk, of which the following is a specification, reference being had to the accompanying drawing, forming part thereof.

Referring to the drawing:

Fig. 1 is a perspective view showing a back, top and one side of my novel desk design;

Fig. 2 is a perspective view showing the front and top thereof; and

Fig. 3 is also a perspective view showing the back and top.

The characteristic features of my design are shown by means of full lines in the drawing.

I claim:

The ornamental design for a desk, as shown and described.

MAX LIVON.
